(57) **CLAIM**

The ornamental design for a light fixture, as shown and described.

DESCRIPTION

FIG. 1 is a bottom view of light fixture showing the claimed design;

FIG. 2 is a top view thereof;

FIG. 3 is a left side view thereof;

FIG. 4 is an enlarged front view thereof;

FIG. 5 is an enlarged rear view thereof;

FIG. 6 is a top perspective view thereof; and,

FIG. 7 is a bottom perspective view thereof.

The broken line disclosure represents unclaimed portions of the light fixture.
